UNITED STATES PATENT OFFICE.

ANTON VON KERPELY, OF VIENNA, AUSTRIA-HUNGARY.

WATER SEAL FOR GAS-PRODUCERS WORKING WITH HIGH-PRESSURE BLAST.

1,078,148.

Specification of Letters Patent.

Patented Nov. 11, 1913.

Application filed December 21, 1912. Serial No. 737,974.

To all whom it may concern:

Be it known that I, ANTON VON KERPELY, a subject of the King of Hungary, residing at Vienna, Austria-Hungary, have invented 5 certain new and useful Improvements in Water Seals for Gas-Producers Working with High-Pressure Blast; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of 15 this specification:

The present invention relates to a further improvement of the water seal of rotary grate gas producers working with high pressure blast such as are described in the 20 specification to the U. S. application filed 11th October 1911 Serial No. 654,156. This improved arrangement of the water seal is intended for those cases when it appears desirable or useful to maintain the ash-pan 25 filled with water. In particular this arrangement is advantageous whenever the producer is working with fuel that yields easily fusible ashes or has the propensity to endothermic working:

30 In the arrangement described in the specification to U. S. application Serial No. 654,156 the maintenance of the ash-pan filled with water is only possible whenever the level of the water in the ash-pan is situated 35 below the bottom end of the shaft. If the water level rises above the bottom end of the shaft the pressure within the producer will force the water above the edge of the ash-pan until the former level is attained. 40 In order to obviate the drawbacks connected with similar temporary overflowing of the water it is necessary to maintain in the exterior annular chamber the same degree of pressure as in the shaft of the gas producer 45 and this is obtained in such a manner that the annular chamber is connected at some place thereof with the blast admission pipe. In such a case the pressures on the water level within and outside of the shaft will

remain equal to each other and the driving 50 out of the water and an overflowing of the same beyond the edge of the ash-pan can no longer take place.

The accompanying drawing is a vertical section of the lower part of the gas pro- 55 ducer and shows by way of example a form of execution of the arrangement according to this invention.

a designates the grate, *b* the rotary ash-pan which carries the grate, *c* the producer 60 shaft, *d* the sheet iron casing which closes the annular chamber *e* to the outward. The blast pipe *w* is connected with the said annular chamber *e* by means of the tube *r* that is capable of being closed by the damper *s*. In consequence of this arrangement the pressure prevailing in the said chamber *e* will be at *y* the same as that which obtains within the shaft *c* at *x*, whereby the over- 65 flowing of the water is rendered impossible; 70 by closing the damper *s* the former conditions can be restored again.

Claim.

In a gas producer, a grate therein, a blast pipe for introducing air under pressure to 75 said grate, a rotary ash-pan carrying said grate surrounding the lower end of the shaft and extending above the same, a water seal for the shaft in said pan, a stationary gas-tight casing forming an annular chamber 80 surrounding the pan and lower end of the shaft and having a gas tight connection with the latter, a pipe connecting the blast pipe and chamber, a damper in the connect- 85 ing pipe to balance the gas or blast pressure exercised on the water within the shaft, said casing forming an air-tight discharge chamber communicating with said annular chamber, means for discharging ashes into the discharge chamber, and means for with- 90 drawing ashes from the latter.

In testimony that I claim the foregoing as my invention, I have signed my name in presence of two subscribing witnesses.

ANTON VON KERPELY.
